CONDENSER

Lyman G. Ketcham, Brooklyn, N. Y., assignor to
 Teleradio Engineering Corporation, New York,
 N. Y., a corporation of New York

Application October 18, 1935, Serial No. 45,584

3 Claims. (Cl. 175—41.5)

This invention relates to improvements in condensers and more particularly to improvements in condensers of the character known to the art as "padder" or "trimmer" condensers.

5 An object of the present invention is to provide a condenser which is substantially unaffected by temperature or humidity changes.

Another object of the invention is to provide a condenser having a base so shaped as to contain a cavity for the reception of the condenser elements whereby these elements are both restricted from undesired movement, and the frangible elements are protected.

Another object of the invention is to provide 15 a condenser in which the base is provided with an element receiving cavity, the walls of which are so shaped as to, in conjunction with formations of the elements, definitely align the elements properly.

20 A further object of the invention is to provide a condenser arrangement wherein the base may be provided with a plurality of cavities for the reception of multiple condenser units, together with means for electrically connecting the adjusting members of the units so that all of the 25 adjusting members can be grounded through a single connection.

A still further object of the invention is to provide a multiple condenser assembly of such 30 character that the units can be independently tuned without causing detuning of the circuits with which the units are associated due to body capacity of the operator.

Another object of the invention is to provide a 35 multiple condenser assembly of such construction that stray capacities between the multiple condensers are minimized.

In carrying out the foregoing and other objects of the invention, the condenser in unitary or 40 multiple form is made up of a molded base of insulating material, which is substantially non-hygroscopic. This base is provided either with a single cavity or with a plurality of cavities. Each cavity is substantially open ended, being defined 45 by opposite walls which are so dimensioned as to receive the condenser elements therebetween. The opposite walls are provided with ribs or bosses which cooperate with recesses or notches in the condenser elements to properly align these 50 elements in the cavity. An adjustment screw passes through the base, through the condenser plates and the interposed dielectric strips, into engagement with a relatively heavy pressure plate which serves to compress such of the plates as 55 are normally bowed. The major portion of each

of the condenser plates is of substantially less width than the space between the cavity walls in order that the interposed strips of dielectric material may effectively insulate the plates. However, these plates are provided with ears 5 which space them relative to the cavity walls, and since it is desired that these ears do not lie directly one above the other, they are so disposed on the condenser plates as to be in staggered relation when the unit is assembled. 10 Since the strips of dielectric material are made of some relatively frangible material, such as mica, etc., the cavity walls serve to protect the overhanging parts of these strips from being frayed or otherwise injured. 15

When the condenser construction is in the nature of a multiple unit assembly, provision is made for grounding the adjustment screws of all of the condensers through a common connection. For this purpose a metallic bar engages 20 each of the adjusting screws in such fashion as to make good electrical connections therewith. This bar in turn can be connected electrically with a grounded part of the chassis or a radio set by means of the same member which is 25 utilized for fastening the assembly to the chassis, or to a shielded can.

Other features, objects and advantages of the invention will become apparent by reference to the following detailed description read in the 30 light of the accompanying drawings, wherein—

Fig. 1 is a plan view of the device embodying the invention.

Fig. 2 is an enlarged section taken substantially on the line 2—2 of Fig. 1. 35

Fig. 3 is an enlarged section taken substantially on the line 3—3 of Fig. 1.

Figs. 4, 5 and 6 are plan views of elements used in the condenser construction.

Fig. 7 is a plan view of a modification of the 40 invention.

Fig. 8 is a similar view of the opposite side of the same device.

Fig. 9 is a plan view of a further modification of the invention. 45

Fig. 10 is a similar view of the opposite side of the same device.

Fig. 11 is a perspective fragmentary view of an assembly utilizing one form of the invention; and 50

Fig. 12 is a section taken substantially on the line 12—12 of Fig. 11.

Referring now to the drawings, 10 indicates a base member, such base member being composed of some suitable insulating non-hygroscopic ma- 55

material, such as a highly compressed ceramic material, thoroughly impregnated with wax or other moisture repellent. This base 10 is provided with an open ended cavity which is defined by 5 the opposite walls 11 and 12. Apertures 14 are provided on opposite sides of the base for the passage of suitable members for attaching the base in a radio receiving chassis, or any other suitable location. The base is also provided with 10 an aperture 15 substantially symmetrically located relative to the walls 11 and 12 and to the open ends of the cavity defined by these walls. The surface of the base member opposite the cavity is provided with a recess 16 as shown clearly in Fig. 3.

The condenser elements used in conjunction with this base consists of condenser plates 20, strips of dielectric material 21; a pressure plate 22, and an adjusting member or screw 24. The 20 condenser plates, two or more of which may be used in a condenser assembly, consist preferably of thin plates of spring brass or bronze which are cadmium or tin plated to facilitate the soldering of electrical connections thereto. These 25 plates 20 are each provided with an aperture 25 of greater diameter than the aperture 15 in the base 10. The strips of dielectric material 21 are in the form of thin sheets of some good insulating material, such as ruby India mica, etc. These 30 strips 21 are also provided with apertures 26 of diameter corresponding to that of the base aperture 15. The pressure plate 22 is made from a metallic plate, preferably of brass, which is cadmium or tin plated. This plate 22 is 35 considerably thicker than the condenser plates 20. The plate 22 is provided with a central aperture 27 the walls of which are extended during the punching operation so that internal threads 23 may be provided for the engagement therewith 40 of the threads on the adjusting screw 24.

The walls 11 and 12 defining the open ended cavity in the base member are provided with oppositely disposed bosses or ribs 28 (Fig. 1). These 45 bosses or ribs serve to properly align the condenser elements relative to the cavity and relative to the base aperture 15. To further this aim, the plates 20 are so constructed that recesses 30 are provided at one end of each plate while the other end is provided with a recess 31 and an opposite recess 32, partially formed 50 by an ear 34. These recesses 30, 31 and 32 are so positioned as to substantially engage portions of the ribs or bosses 28. Since the major portion of each plate 20 is of less width than the 55 width of the cavity defined by the walls 11 and 12, spacing members are formed on the edges of the plates to assure that the plates will fit properly between these walls. As shown in Fig. 4 the plate 20 is provided near one end with 60 ears 35 and near the other end with ears 36. These ears 36 are closer to their respective end of the plate than the ears 35 are to their end of the plate. The purpose of this construction is to assure that the ears of one plate will not be 65 directly aligned with the ears of another plate of the condenser assembly, it being understood that one plate of the assembly will be in reversed position relative to another plate in the assembly. A suitable terminal member 37 extends 70 upwardly from one end of the plate 20.

The strips of dielectric material 21 have their ends provided with concavities 38 to engage portions of the ribs or bosses 28. The pressure plate 22 has its ends provided with concavities 39 75 spaced from the bosses 28. This pressure plate

22, however, is a slight bit shorter than the condenser plate 20 so that when the device is assembled the possibility of an end of the pressure plate contacting with the terminal 37 is substantially prevented.

The condenser unit is assembled substantially as follows: A condenser plate 20 is positioned in the cavity of the base with the undersurface of the plate 20 resting flat against the bottom of the cavity. A strip of dielectric material 21 10 is then placed directly over the top surface of the plate 20. A second plate 20' is placed on top of the first strip of dielectric material 21. Since it is desired that the condenser be adjustable, this second plate 20' is bowed substantially 15 throughout its length so that when no pressure is applied to this upper plate the upper plate is separated from the strip of dielectric material throughout the major portion of its length. A second strip of dielectric material 21' is then 20 positioned on top of the top plate 20' and the pressure plate 22 is then positioned to overlie this upper strip of dielectric material 21'. With these parts in this position, proper alignment 25 being assured by the various recesses in the members engaging the ribs or bosses 28, they may be locked in position by means of the adjusting screw 24 which passes through the base aperture 15 through the apertures 25 and 26, 30 into threaded engagement with the wall of the pressure plate aperture 27. This adjusting screw 24 can be turned until the condenser unit is in a condition shown in Fig. 3, wherein the upper plate 20' is flattened out firmly against the lower dielectric strip 21. In this condition the condenser has its maximum capacity. Of course 35 the screw 24 can be turned to permit the bowed upper plate 20' to flex and separate throughout the major portion of its length relative to the lower plate, the amount of bow in this upper plate determining the capacity of the condenser, which decreases as the upper plate becomes more separated from the lower plate. Since plates 20 and 20' are in opposite positions 40 as indicated by their respective terminals 37 and 37', it will be apparent that the spacing ears 35 and 36 of the respective plates will be in 45 staggered relation. Thus these plates are definitely locked in the cavity, and at the same time the spacing ears are out of register so that 50 chances of one plate coming in direct contact with another plate are prevented. The provision of the upstanding walls 11 and 12 assures that with the plate arrangement shown 55 the plates will not be capable of any substantially shifting of position during adjustment, and, moreover, these upstanding walls serve admirably to protect the edges of the relatively fragile strips of dielectric material, it being understood 60 that these strips are of such width as to extend beyond the major portion of the various condenser plates.

A condenser constructed and assembled as just described possesses all of the advantages set forth hereinbefore, namely, the condenser is adjustable 65 with a minimum of drift of capacity change due to temperature or humidity changes; the edges of the dielectric material are protected by the cavity walls; the various elements of the unit are definitely positioned in the cavity; and the 70 unit possesses adjustability within desired ranges. While the desired assembly has been shown as being constructed simply of a pair of plates 20 and 20', it should be understood that additional plates similar to plate 20' can be applied in the 75

assembly in the event it is desired to increase the capacity of the unit in which event the additional plates would be connected electrically alternately to the plate 20 and plate 20'. Each 5 additional plate will be bowed, of course, and each additional plate will be insulated from the other elements by similar strips of dielectric material similar to strip 21'. The prevention of drift or capacity change can be aided by connecting the unit in a suitable circuit in such 10 fashion that the plate 20 is connected to be at low potential.

While the base 10 just described has been illustrated as having therein a single cavity for 15 a condenser unit, the base may be constructed to have a plurality of cavities for the reception of a plurality of condenser units so that the device may assume the form of a gang or multiple condenser assembly. In Figs. 7 and 8 the base 50 20 is provided with walls 51 and 52 defining one cavity and with walls 54 and 55 defining another cavity. A condenser unit A is shown positioned in the cavity defined by the walls 51 and 52, while a similar unit B is shown in the cavity defined by the walls 54 and 55. The walls 51, 52, 25 54 and 55 are constructed entirely in accordance with the walls 11 and 12 and the various elements of the condenser elements A and B correspond to the various elements shown in Figs. 1 to 6, 30 inclusive. It should be understood, of course, that any number of plates can be used in these units A and B to obtain the desired capacity range. The other side of the base 50 is provided with an enlarged recess 56, the ends of which 35 are arcuate shape as at 57 for the reception of a rounded end strip of metal 58. This strip of metal is provided with apertures through which the shanks of adjusting screws C and D may pass, so that the heads of these screws will bear 40 against the exposed surface of the strip. The strip is also provided with an aperture 59 in alignment with the central aperture 60 of the base. The base may be provided with additional apertures 61 if desired.

45 The aperture 59 is provided in the strip 58 (the strip 58 being preferably of cadmium plated brass) for the passage of any suitable member or stud for attaching the gang condenser assembly, either to a shield or to any other grounded member of a receiving set or to even a grounded conductor. The shield or chassis of the set can be grounded so that the adjustment screws C and D are in ground potential. Thus the gang condenser is effectively and electrostatically 50 shielded in that the adjustment screws are at ground potential, permitting the use of a metal adjusting tool without causing such detuning of the circuits in which the condensers are used as normally occurs due to the body capacity of the 55 one adjusting the condensers.

An illustration of the manner in which the gang condenser of Figs. 7 and 8 can be used with other parts of a receiving set is shown clearly in Figs. 11 and 12 wherein a threaded rod or stud 60 65 70 having a nut 71 immovably secured intermediate the ends thereof passes through the opening 59 of the plate 58, through the opening 60 into the threaded bore 72 of a rod of insulating material 74 on which the inductances 75 of a transformer unit can be wound. The threaded portion 76 of the rod 70 extending beyond the nut 71 may be used to secure the transformer unit in a shielded can or to any other suitable part of the chassis. A simple nut will suffice to 75 make this installation. It should be understood,

of course, that the shielded can or other support will have apertures aligned with the heads of the adjusting screws C and D for the passage of a suitable tool utilized in adjusting the respective condensers A and B.

In the modification shown in Figs. 9 and 10, a base 81 is provided with walls 82, 84, 85, 86, 87 10 and 88: the pair of walls 82 and 84 defining a cavity for the reception of a condenser unit E; the pair of walls 85 and 86, defining a cavity for 15 the reception unit F; and the walls 87 and 88 defining a cavity for the reception of a condenser unit G. The construction of the various walls and of the condenser units is similar to the constructions heretofore described. A metallic bar 15 90 similar to the bar 58 is positioned in a recess 91 in the opposite surface of the base 81, such bar 90 being provided with apertures for the passage of the shanks of adjusting screws H, J 20 and K associated with the respective units E, F 25 and G. Rods or studs similar to the rod 70 pass through openings in the bar 90 and in the base 81 so that the nut portion 94 of each stud is fastened securely against the upper surface of the bar 90. The shank portion of these rods may 30 be engaged by nuts 95 on the cavity side of the base 81. The corresponding portions 96 of the rods or studs may be used to attach the gang condenser assembly to a suitable shield or other support, which preferably, can be grounded. 35 Thus a good electric connection between the various adjusting screws H, J and K is provided, and if this bar 90, which provides the connection is grounded, it is possible to adjust the capacity of any one or all of the condensers E, F, or G without causing such detuning of the circuit with which the condenser is associated as normally occurs due to the body capacity of the one adjusting the condenser.

While the gang condenser assemblies have been 40 shown embodying assemblies of two and three units, it will be apparent that the number of units in a gang assembly can be increased as occasion may demand. In any form of gang assembly, the present invention provides an arrangement 45 in which adjusting screws can be kept at grounded potential thereby facilitating adjustment without interfering with the characteristics of the circuits including the condensers. Moreover, the form of base shown aids in preventing stray 50 capacities between the units of a multiple condenser assembly. Also if the low potential plate is positioned adjacent the insulating material of the base, such stray capacities are further minimized.

55 While the cavities shown in the various embodiments of the invention have been shown and described as being substantially open ended, it is to be understood that the invention is not to be limited to such arrangement. The open ended 60 cavities are provided to facilitate the attachment of conductors to the plate terminals, but it is contemplated that these cavities could have end walls as well as side walls.

I claim:

1. A device of the character described comprising a molded base of insulating material having a plurality of cavities therein, a condenser unit in each of said cavities, individual adjusting members for varying the capacities of said units, 70 and a single member secured to said base and electrically connected to said adjusting members whereby all of said adjusting members can be grounded with a single ground connection.

2. A device of the character described compris- 75

ing a molded base of insulating material having a plurality of cavities therein, a condenser unit in each of said cavities, individual adjusting screws passing through said base and cooperating with a pressure plate in each condenser unit for varying the capacity of said units, and a bar secured to said base and having apertures therein through which said adjusting screws pass to electrically connect all of said adjusting screws.

10 3. A device of the character described comprising a molded base of insulating material having a plurality of cavities therein, a condenser unit in each of said cavities, individual adjusting

screws passing through said base and cooperating with a pressure plate in each condenser unit for varying the capacities of said units, a bar having apertures therein through which said adjusting screws pass to electrically connect all of said 5 adjusting screws, and at least one connecting member connecting said bar to said base and being adapted to connect said device to a supporting structure, said connecting member being adapted to serve as a common ground connection to ground all of said adjusting screws. 10

LYMAN G. KETCHAM.
